GRAIN MILL

James M. Conner, Glendale, and William F. H. Purcell,
Pasadena, Calif., and Etilar A. Henningsen, Geneseo,
and John E. Hoffman, Moline, Ill., assignors to Deere
& Company, Moline, Ill., a corporation of Delaware

Filed July 25, 1962, Ser. No. 71,045

Term of patent 14 years

(Cl. D40—1)

FIG. 1

FIG. 2

FIG. 5

FIG. 6

FIG. 1 is a perspective view taken from the front and right side of the grain mill showing our new design.

FIG. 2 is a perspective view taken from the right side thereof.

FIG. 3 is a perspective view taken from the rear and right side thereof.

FIG. 4 is a perspective view taken from the front thereof.

FIG. 5 is a perspective view of a modified form of the grain mill taken from the front and side;

FIG. 6 is a perspective view taken from the rear and side thereof.

The side not shown is substantially the same as the side shown.

What is claimed is:

The ornamental design for a grain mill, substantially as shown and described.
